United States Patent Office.

IRA D. RICHARDS AND HENRY D. SNYDER, OF CARBONDALE, PENNSYLVANIA.

Letters Patent No. 77,842, dated May 12, 1868.

IMPROVEMENT IN FENCE-POSTS.

The Schedule referred to in these Letters Patent and making part of the same.

TO ALL WHOM IT MAY CONCERN:

Be it known that we, IRA D. RICHARDS and HENRY D. SNYDER, both of the city of Carbondale, county of Luzerne, and State of Pennsylvania, have invented a new and improved Fence-Post; and do hereby declare that the following is a full and exact description thereof, reference being had to the accompanying drawings, and to the letters of reference marked thereon.

The nature of our invention consists in a cast-iron post, to set in the ground, about two feet deep, formed with a broad, flat bottom, and winged to prevent it from being raised, or thrown to either side by the action of the frost, and to extend some sixteen (16) inches or more above the ground. That portion of the post above the ground has a dove-tail groove on one side, into which an iron tenon or tongue is made to fit, and slides in from the top, and rests upon a shoulder at the bottom of the dove-tail groove. The iron tenon or tongue is fastened to the wooden post, by means of large screws or bolts, into which wooden posts mortises are made to receive the horizontal rails, upon which the fence is built, in any usual manner.

To prevent water remaining in the dove-tail groove after rains, we put one or more holes through the shoulder, at the bottom of the dove-tail groove, in such manner as to allow the water to drain through upon the ground; and to prevent the cast iron from rusting, we galvanize it when required.

To enable others skilled in the art to make and use our invention, we will proceed to describe its construction and operation.

We construct our fence-post, the bottom part of cast iron, and the top of wood, with a cast-iron dove-tail tongue or tenon fastened on it, with screws or bolts, which tongue or tenon slides into a dove-tail groove that is formed in the top of the cast-iron post, by which means the wood is fastened to the cast-iron part of the post D. We construct the cast-iron part with a flat flanged bottom, as represented in drawings Nos. 1 and 2, marked N, with wings extending up about two feet, marked M, to a shoulder at the bottom of the groove, through which shoulder one or more holes are made, as shown by cross-section, through E F, plate No. 4. The formation of the dove-tail is shown by diagram No. 3, cross-section through A B. Letter C, in drawing No. 1, represents the wooden post as fastened to the cast-iron bottom, it being a side view. Drawing No. 2 represents a front view of the same. Letter D represents the cast-iron part of the post.

What we claim as our invention, and desire to secure by Letters Patent, is—

The fence-post, with cast-iron bottom and wood top, as herein described and for the purposes set forth.

IRA D. RICHARDS,
HENRY D. SNYDER.
